CABINET

Florence J. Sterling, Chicago, Ill., assignor to Sterling-Freeland Industries Inc., Chicago, Ill.,
a corporation of Illinois

Application June 19, 1952, Serial No. 20,255

Term of patent 3½ years

(Cl. D33—19)

To all whom it may concern:

Be it known that I, Florence J. Sterling, a citizen of the United States of America, residing at 4701 N. Western Avenue, Chicago, Illinois, in the county of Cook and State of Illinois, have invented a new, original, and ornamental Design for a Cabinet, of which the following is a specification, reference being had to the accompanying drawing, forming a part thereof, wherein:

Fig. 1 is a perspective view of a cabinet, viewed from the front and side, showing my new design; and

Fig. 2 a perspective view thereof, showing the front and opposite side, the drawer being illustrated in slightly opened position.

The dominant features of my design reside in that portion of the cabinet illustrated in full lines.

I claim:

The ornamental design for a cabinet, as shown and described.

FLORENCE J. STERLING.
